GUARD FOR COMBING MACHINES FOR
COMBING TEXTILE FIBERSDonald Pierrepont, Chadderton, Oldham,
EnglandApplication May 8, 1943, Serial No. 486,147
In Great Britain April 18, 1942

9 Claims. (Cl. 19—115)

This invention relates to guards for combing machines for combing textile fibers and has for its primary object the provision of a guard which affords the maximum protection of moving parts of the machine and reduces to a minimum the possibility of injury to an operative who may attempt to tamper with the machine whilst it is in motion. A further object is to minimise risk of damage to the machine caused by the machine being set in motion when a part, or parts, of the working mechanism is, or are, out of operative position.

It is well known that in the working of a combing machine operatives are prone to tamper with the machine while it is in motion, and in so doing are liable to get their hands caught in the machinery, or to cause damage to the machine through insertion of a picker, key, or other instrument into the mechanism.

The invention contemplates the provision of a guard which covers substantially all the moving mechanism at the front of a combing machine, that is mechanism located within a field of operation between the creel uprights and the sliver table, is locked in closed position when the machine is in motion and cannot be opened until the machine is stopped or about to be stopped, and which, when open, prevents the machine from being set in motion, motion of the machine being possible only when all the elements of the mechanism are in correct working position and the guard is restored to closed position.

The invention consists in a guard device which may be in one piece or in articulated sections, adapted to cover the whole of the front of the combing machine, extending from the creel uprights to the front sliver table, thereby encasing moving parts such as detaching-rollers, detaching-roller weighting hooks, detaching-roller rocking-motions, top comb, needled cylinder, and calender rollers on the sliver table, said guard device incorporating balancing means to facilitate the raising and lowering of the guard by an operative, locking means, and preferably also means permitting usual inspection of the working of the machine, for example, to see that the fibers are being correctly combed or to see when roller laps or other faults occur. The guard is arranged to co-operate with means for preventing the suction-box lids at the rear of the machine from being opened while the machine is in motion, and, if the suction-box lids are open, to prevent the machine from being set in motion until all the said lids are restored to their closed position.

The guard preferably comprises a row of sec-

tions of which each section serves to cover at least one delivery head of the machine, the sections at the ends of the row being each provided with an end plate and intermediate sections being

5 interchangeable.

Some embodiments of the invention will now be described with reference to the accompanying drawings in which only so much of a combing machine is illustrated as is necessary for a 10 clear understanding of the invention.

In the drawings Fig. 1 is a perspective view of the gearing end of a combing machine showing a guard in the closed or covering position on the front sliver table; Fig. 2 is a fragmentary perspective view drawn to a larger scale of the guard in its open or raised position; Fig. 3 is a sectional view, drawn to a still larger scale, of a means for retaining the guard in raised position; Fig. 4 is a fragmentary side view showing the 15 guard in full lines in its closed position and in broken lines in its raised position and also showing additional means for retaining the guard in its raised position against accidental displacement; parts of the combing machine mechanism 20 later to be referred to are also shown. Fig. 5 is a fragmentary perspective view looking at the inside of the guard and showing how the guard is prevented from closing when the detaching roller weighting is in the "off" position and also showing means for locking the guard when it is fully 25 closed. Figs. 6 and 7 are fragmentary plan and side views, respectively, drawn to a larger scale, of parts of the locking means shown in Fig. 5 in the position occupied when the guard is open. 30 Figs. 8 and 9 are similar views showing the parts in the position occupied when the guard is locked. Fig. 10 is a vertical section through the guard in closed position, also showing, more or less diagrammatically, some of the parts of the combing 35 machine enclosed by the guard. Fig. 11 is a plan of Fig. 10 and shows one construction of guard according to the invention. Figs. 12 and 13 are similar views to Figs. 10 and 11 but showing a modified construction of guard. Figs. 14 and 40 15 are also similar views to Figs. 10 and 11 but showing a further modified construction of guard. Fig. 16 is a fragmentary side view, drawn to a larger scale, of a modified form of the brake mechanism shown in Fig. 1 and later to be described; Fig. 17 45 is a front view of the brake mechanism shown in Fig. 16 with parts in the position occupied when the machine is stopped or the brake is "on"; Fig. 18 is a similar view to Fig. 17 with parts in the 50 position occupied when the machine is running and the brake is "off"; Fig. 19 is a similar view

to Fig. 17 with the parts in the position occupied when the machine is stopped and the brake has been released by hand; Fig. 20 is a fragmentary perspective view showing the guard raised and prevented from being lowered because of the top comb of the combing machine being out of operative position; Fig. 21 is a fragmentary perspective rear view of the gearing end of a combing machine showing locking means for preventing the opening of the suction-box lids when the combing machine is working; Fig. 22 is a similar view showing a modified form of the locking means shown in Fig. 21. Figs. 23 and 24 are fragmentary views, drawn to a larger scale, of a detail part of the mechanism shown in Fig. 22 in alternative positions of use; Fig. 25 is a fragmentary view, also drawn to a larger scale, of a further detail part of the mechanism shown in Fig. 22.

The same reference characters indicate corresponding parts in the several figures of the drawings.

Referring to Fig. 1, which shows in perspective the gearing end of a Nasmith combing machine, 10 indicates the frame of the machine, 11 one of the creel uprights, 12 the creel, 13 the front sliver table, 14 the setting-on rod with its operating handle 15; 16 the gear box; 17 the driving shaft; 18 a bearing bracket carried by the stand 19 supporting the gear box 16; 20, 21 the fast and loose pulleys, respectively; 22 the driving belt; 23 the flywheel; 24 the belt-shifter, to which the setting-on rod 14 is operatively connected by a linkage 25; and 26 the top front calender roller, all of known construction. 27 is a guard section, hereinafter referred to as a cover, adapted to cover the moving parts of one head of a combing machine, said cover being preferably constructed of sheet metal and conforming approximately to the contour of the combing machine. The cover 27 extends from the creel uprights 11 to the front sliver table 13 on which it rests at its lower front edge when in the closed position as shown in Fig. 1. The cover 27 is formed with a sloping top and is provided with a transparent window 28 and with two box-like extensions 29.

The main body of the cover 27 is adapted to encase the needled cylinder 30, feed rollers 31, nippers as 32, top comb 33, detaching rollers 34 and detaching-roller weighting mechanism 35, while the box-like extensions 29 are adapted to encase the nipper weighting mechanism, see Fig. 10. The front of the cover 27 is cut away at 27a to allow the cover to fit over the top calender roller 26 and to allow the operator to obtain limited access to the top calender roller.

Referring to Figs. 2, 3 and 4, the cover 27 is hingedly connected at its upper end on opposite sides to brackets attached to the creel uprights 11. One of said brackets 36 is shown in Fig. 2 and has fixed therein a hinge pin 37 upon which is threaded a torsion spring 38 having one end secured in a collar 39 fast on the hinge pin 37, the other end being secured in the boss of a bracket 40 secured to the inside of the cover 27, see particularly Figs. 2 and 3. A corresponding hinge connection is provided at the opposite side of the cover 27. When the cover is lowered, the respective torsion springs 38 are wound up, thus balancing the weight of the cover and facilitating the raising of said cover by the operative.

To minimise noise and jar when the cover 27 is lowered on to the front sliver table 13, the lower front edge of the cover may be provided

with a resilient pad indicated at 41, Fig. 2, which also ensures a close fit of the cover on the table.

To guard against accidental displacement of the cover 27 when in the raised position, a catch 5 is provided to lock the cover automatically as it reaches full open position. Such a catch is illustrated in Fig. 4 and consists of a two-armed trigger 42 pivoted in the bracket 40, one arm of said trigger being adapted to slide over and engage a projection 36a on the bracket 36, see dotted lines in Fig. 4, while the other arm is adapted to serve as a handle by means of which the trigger may be manually tripped to release the cover.

To enable the cover 27 to be locked in its closed position there is provided on the front sliver table a locking box 43, see Fig. 5, housing a spring-urged detent 44 adapted to lie in the path of movement of a locking arm 45 fast on the setting-on rod 14 of the machine. The locking arm 45 projects beneath the front sliver table 13 towards the interior of the machine to a point inside the cover, when the latter is in closed position on the front sliver table, and is there bent at right-angles to provide a bolt portion 45a adapted to project through the walls of the locking box 43 and formed with a notch 45b into which the spring-urged detent 44 projects when the cover 27 is raised, see Figs. 6 and 7, whereby endwise movement of the setting-on rod 14 to start the machine is prevented.

Secured to the inside of the cover 27, in correspondingly opposite position to the detent 44, is a bracket formed with a hook-ended projection or finger 46. When the cover 27 is lowered, the finger 46 abuts against and presses back the spring-urged detent 44, see Figs. 8 and 9, whereupon the setting-on rod 14 may be moved in known manner to start the machine. This movement of the setting-on rod 14 causes the locking-bolt 45a to engage with the finger 46, see Figs. 8 and 9, whereby to lock the cover 27 in position. When the setting-on rod 14 is moved in the reverse direction in stopping the machine, the locking bolt 45a is withdrawn from engagement with the finger 46, whereupon, when the cover 27 is raised, the finger 46 is moved away from the spring-urged detent 44 in the locking box 43 and permits said detent to be advanced by the spring into initial position in the path of the locking bolt 45a, see Figs. 6 and 7, thus preventing endwise movement of the setting-on rod 14 to put the machine in motion.

The cover 27 cannot be closed when the detaching rollers are unweighted, as the bottom edge of said cover would foul the weighting-levers 35, see Fig. 5, in which the weighting-levers 35 are shown in the unweighted position, thus preventing further movement of said cover.

Should an attempt be made to close the cover 27, when the detaching rollers 34 are unweighted, by edging said cover past the weighting-levers 35, cam-forming blocks 47 secured to the inner surface of the cover are adapted to abut against and move the weighting levers 35, whereby weighting of the detaching-rollers 34 is automatically effected. There is a cam-block 47 for co-operation with each weighting-lever 35, see Fig. 5.

To prevent closing of the cover 27 when the top comb 33 is raised out of working position, a projection 48 may be provided on the underside of the cover 27, so positioned that, if attempt be made to close the cover 27 with the top comb 33 out of working position, the said projection would come into contact with the

bridge 49 carrying the top comb 33 and prevent any downward movement of the cover 27, see Figure 20. Therefore, until the top comb 33 is in proper working position, it is not possible to close the cover 27.

If for any reason the weight has been taken off the nippers while the cover is raised, subsequent closing of the cover while the nippers are unweighted is prevented. Prevention of closing may be accomplished by the provision of lateral projections on the nipper-weighting release-catches which are arranged at opposite sides of the head, said projections being directed inwardly towards each other and adapted, when the cover is raised and the nipper-weighting release-catches are in the raised position with the weight off the nippers, to lie in the path of movement of the cover whereby to prevent said cover from being lowered until the weighting has been restored to the nippers.

A preferred arrangement for this purpose is illustrated in Figs. 2 and 4. Fig. 2 illustrates nipper weighting and release mechanism of known construction, the weighting being applied to the nippers 32 by means of tension springs, one of which is shown at 50 in Figs. 2 and 10, the tension being applied to the spring by means of a handle 51 pivotally mounted in a bracket 52 carried by the machine frame and in operative connection with the nippers 32 by means of a linkage 53, said handle being held in operative position by a pawl 54 engaging in a notch 52a in the bracket 52, as shown in Figs. 2 and 10, and more particularly in full lines in Fig. 4. There is a corresponding mechanism at the opposite side of the head.

When the cover is raised and it is desired to release the pressure on the nippers 32, the handle 51, and its opposite number, are simultaneously rocked about their respective pivots to free the pawls 54 and allowed to assume the position shown in chain-dotted lines in Fig. 4. If attempt be made to close the cover 27 while the nippers 32 are still unweighted, a projection 55 on the underside of the cover 27, see Fig. 4, abuts against the handle 51 and prevents further downward movement of the cover. There is a corresponding projection on the opposite side of the cover. It will therefore be understood that, while the nippers 32 remain unweighted, it is impossible to close the cover 27.

In order to ensure that the cover 27 cannot be raised until the machine is more or less at a standstill, there are provided means, co-operative with the setting-on rod 14, so arranged that, as the setting-on rod 14 is moved in the direction to stop the machine, as by transferring the belt 22 from the fast pulley 20 to the loose pulley 21, a brake is applied to the flywheel 23, whereby quickly to decelerate the machine, so that, if attempt be made to raise the cover 27 instantly on operation of the belt-shifter 24, by the time the cover is raised the machine will be at a standstill.

One embodiment of mechanism for effecting this braking action is illustrated in Fig. 1, in which 56 indicates a brake-block having a friction lining of suitable material. Said brake-block is pivotally mounted on the bracket 18 forming a bearing for the pulley shaft 17 in close proximity to the underside of the flywheel 23. The brake-block 56 is normally urged towards the flywheel 23 by a tension spring 57 anchored at one end to an extension 58 of the brake-block and at the other end to the stand 19.

At the opposite side of the brake-block 56 to the extension 58 is a projecting arm 59 lying alongside a bracket 60 secured to the bearing bracket 18. The outer end only of said arm is shown in Fig. 1, but it is to be understood that said arm is identical with the arm 59' shown clearly in Fig. 16. The bracket 60 is formed with a slot 61 adapted for penetration by a bolt 62 pivotally attached to a lever 63 fast on the rocker-shaft 64 of the belt-shifter 24. The lower face of the bolt 62 is inclined adjacent to its free end so that in effect the bolt embodies a cam face adapted to co-operate with the upper face of the projecting arm 59. The rocker-shaft 64 is in operative connection with the setting-on rod 14 through the linkage 25.

When the machine is started, endwise movement of the setting-on rod 14, in the direction of the arrow A, causes the rocker-shaft 64 to rock about its bearings to move the belt-shifter 24 and transfer the belt 22 from the loose pulley 21 to the fast pulley 20, whereupon the bolt 62 is caused to slide through the slot 61 in the bracket 60 and by its inclined lower face to bear against and depress the arm 59 to move the spring-influenced brake-block 56 out of contact with the flywheel 23, thus releasing the brake.

When the machine is to be stopped, endwise movement of the setting-on rod 14 in a reverse direction, as indicated by the arrow B, to move the belt 22 from the fast pulley 20 to the loose pulley 21, causes the rocker-shaft 64 to be turned about its axis in the reverse direction, thereby moving the bolt 62 back to initial position, whereupon the spring-influenced brake-block 56 is caused to bear on the surface of the flywheel and to bring the machine to a practically instantaneous standstill.

An alternative and preferred form of brake-mechanism is illustrated in Figs. 16, 17, 18 and 19. Parts of the brake mechanism described with reference to Fig. 1 are designated by the same reference characters with the addition of the distinguishing exponent 1.

Referring to Figs. 16, 17, 18 and 19, the brake-block 56' is pivotally mounted on a stud 65 secured in the bracket 60' by a set-screw 66. The bracket 60' is secured to the bearer bracket 18' by bolts 67 and is formed adjacent to the end remote from the pivot 65 with a slot 61' for penetration by a bolt 62' pivotally mounted on an arm 63' fast on the rocker-shaft 64'. The bracket 60' is formed at the slotted end with a depending cylindrical boss 68 that houses a compression spring 69 adapted to exert pressure against the projecting arm 59' of the brake-block 56', whereby normally to urge the brake block 56' into contact with the surface of the flywheel 23', see Fig. 16. The stress of the spring 69 is adapted to be adjusted by means of an adjusting screw 70 retained in its position of adjustment in the bottom of the cylindrical boss 68 by a lock-nut 71.

When the machine is started, endwise movement of the setting-on rod 14, as before described, to move the belt 22 from the loose pulley 21 to the fast pulley 20 causes the bolt 62' to slide through the slot 61' and to bear with its inclined face 62'' against the projecting arm 59' which, in the embodiment shown, is guided in a slot 60'' in the bracket 60' penetrating an extension 60''' of said bracket, the slot 60'' being disposed at right angles to the slot 61', the depression of the arm 59' rocking the brake-block 56' about its pivot 65 to move the brake-block 56' out of

contact with the flywheel 23', thus releasing the brake, see Fig. 18. Movement of the setting-on rod 14 in the reverse direction to stop the machine causes the bolt 62' to be moved to initial position, see Fig. 17, whereupon the brake-block 56' is caused to bear on the surface of the flywheel 23' to arrest the flywheel 23' and to bring the machine to a standstill.

To allow turning movement of the machine by hand when desired, an eccentric 72 is pivoted at 73 in the extension 60''' and is furnished with a projecting arm or finger 74 whereby the eccentric 72 may be turned about its pivot 73 to press on the arm 59' and release the brake, see Fig. 19. Movement of the belt-shifter to start the machine automatically returns the eccentric 72 to initial position.

One embodiment of the means provided to prevent the opening of the suction-box lids at the rear of the machine while the machine is in motion, and to prevent restarting of the machine until the suction-box lids are properly closed, is illustrated in Fig. 21. Referring to Fig. 21, 75 is a slide-rod extending lengthwise of the machine and slidable in bearing brackets 76 attached to the rear of the machine frame 10. The rod 75 is connected at one end to a lever 77 fast on the rocker-shaft 64 of the belt-shifter.

Threaded on the rod 75 are a number of projecting arms, one of which is shown at 78. An arm 78 is fixed to the rod 75 adjacent to each of the suction-box lids of the respective delivery heads of the machine. 79 indicates one of said suction-box lids and 80 a suction-box. The disposition of the projecting arms 78 is such that, when the machine is in motion, an arm 78 projects into the path of movement of the respective suction-box lid 79, see Fig. 21, the free extremity of the arm 78 being then so closely adjacent to the lid 79 that it is impossible to raise said lid sufficiently to obtain even limited access to the suction-box 80.

When the setting-on rod 14 is moved in a direction to stop the machine, i.e., in the direction indicated by the arrow B in Fig. 1, the rod 75 is correspondingly moved through the medium of the lever 77 on the rocker-shaft 64, and the projecting arms 78 are moved out of the path of movement of the suction-box lids 79, which may then be opened.

The ultimate position of the projecting arm 78 shown in Fig. 21 is shown in chain-dotted lines in that figure. The position of the arms 78 relatively to the suction-box lids 79 is such that not until the rod 75 has moved to practically its extreme ultimate position do the arms 78 move clear of the suction-box lids 79 to free said lids.

When the machine is stopped and a suction-box lid 79 is raised, the machine cannot again be set in motion until said lid is properly closed. If an attempt be made to move the setting-on rod 14 and with it the rod 75, the projecting arm 78 adjacent to the open suction-box lid 79 would come into contact with the edge of the raised lid and prevent endwise movement of the rod and starting of the machine.

An alternative and preferred form of means for preventing the opening of the suction-box lids while the machine is in motion, and preventing restarting of the machine until the suction-box lids are properly closed, is shown in Figs. 22, 23, 24 and 25. Parts in these figures corresponding to parts in Fig. 21 are indicated by corresponding reference characters distinguished by the exponent 1.

In this construction, the slide rod 75' carried in bearing brackets 76' is connected at one end to the lever 77' by means of a connection which permits of turning movement of the rod 75' in addition to endwise movement. This connection comprises a socket 81 pivotally connected to the lever 77' of the rocker-shaft 64. The adjacent end of the rod 75' fits into a socket part 82 and is formed with an annular recess 75'' into which projects the end of a set-screw 83 screw-threaded into the socket 81, whereby the rod 75' is secured in the socket against withdrawal while permitting turning movement of the rod 75' relative to the socket 81.

A torsion spring 84 threaded on the rod 75' is anchored at one end in the socket 81 and at the other end in a collar 85 secured by a grub-screw 86 on the rod 75', see Fig. 25. The collar 85 is adapted to be turned relatively to the rod 75' to regulate the torsion of the spring 84. At least one of the brackets 76' is formed with a key-way 87, and a key 88 in the rod 75' is adapted, in one position of use, to register with, and be engageable in, said key-way, see Fig. 23.

The arms 78' are so arranged that each arm is approximately in mid-position of the suction-box lid 79' with which it co-acts when said lid is closed, the free end of each locking arm 78' being closely adjacent to the respective suction-box lid.

Assuming the combing machine to be working and the suction-box lids 79' to be locked, as in Fig. 22, the rod 75' is restrained against rotation by the key 88 engaging in the key-way 87 in the bracket 76', see Fig. 23, and, therefore, with the ends of the locking arms 78' in close proximity to the suction-box lids 79', unauthorized opening of a suction-box lid is effectually prevented.

When the belt-shifter is moved from the fast to the loose pulley position to stop the machine, the rod 75' is moved endwise and the key 88 is slid out of the key-way 87, see Fig. 24, leaving the rod 75' free to be turned. An operator desiring to raise a suction-box lid raises one of the locking arms 78' and rocks the rod 75' about its axis, thus moving the key 88 out of register with the key-way 87, and the suction-box lid is then free to be opened. If attempt be made to restart the combing machine while a suction-box lid remains open, the key 88 on the rod 75' being out of register with the key-way 87 in the bracket 76' and abutting against said bracket would prevent endwise movement of the rod 75' and therefore make it impossible to move the belt-shifter to restart the machine.

With all the suction-box lids 79' closed the locking arms are returned to the locking position by the turning movement of the rod 75' and the key 88 is again brought into register with the key-way 87 so that the rod 75' is free to be moved endwise by the belt-shifter in starting the machine, the key 88 again entering the key-way 87 and locking the arms 78'.

To ensure that the key 88 shall correctly register with the key-way 87 in the return movement of the rod 75', there is formed on the bracket 76' a rabbet 76'' against which the key 88 comes into contact in the reverse movement of the rod 75', see Fig. 24.

It will be seen that unauthorized opening of a suction-box lid while the combing machine is in motion is effectually prevented, and also that, after the combing machine has been stopped, and a suction-box lid has been opened, it is impossible to restart the combing machine while a lid remains open.

A modified form of cover is shown in Figs. 12 and 13 in which the cover 27 is provided with a transparent flap 28a hinged on a rod 27b pivoted in the cover 27 and furnished at its ends with torsion springs 27c adapted to return the flap 28a to initial position after it has been turned downwards to the position shown in chain-dotted lines in Fig. 12.

When so turned down the flap 28a, while permitting access to be obtained to the front sliver tin indicated at 89, also serves as a guard to keep the fingers of the operative from contact with moving parts of the machine.

A further modification is shown in Figs. 14 and 15 in which the cover 27 is formed with a recessed part 27d which permits unrestricted access to the front sliver tin 89 and to the front calender rollers 26. The rear of the recess is closed by a wall 27e.

The transparent window 28 in the cover 27 permits unrestricted visual inspection of the working of the delivery head.

It will be seen that with the use of a guard constructed as described the risk of injury to an operative by contact with moving parts of the machine is reduced to a minimum. Risk of damage to the machine caused through setting the machine in motion while any of the working parts are out of proper position is also reduced to a minimum.

Guard devices constructed according to the invention afford maximum protection to the operative and to the machine without impairing the working efficiency of the machine.

The described guard devices may be applied to existing machines without structural alteration or with a minimum of alteration, as full use is made of existing parts to obtain the desired effects of the guard.

What is claimed is:

1. In a combing machine for combing textile fibers including a frame, creel uprights extending above said frame, a front sliver table, and mechanism located within a field of operation at the front of the machine, between said uprights and said sliver table, the combination of movable guard means adapted when in a lower position to encase substantially all of said mechanism and when raised to an upper position to expose said mechanism, means for starting and stopping the machine, means effective to prevent said guard means from being raised to upper position until said last named means is moved to machine-stopping position, means effective to prevent said guard means from being lowered to lower position unless said mechanism is in correct working position, means to prevent starting of the machine when said guard means is in its upper position, suction boxes at the back of the machine, said suction boxes having lids, and means interlocked with said starting and stopping means for preventing said lids from being opened while the machine is in operation, and for preventing the machine from being started while a lid is open.

2. The combination claimed in claim 1 in which the guard means is mounted on at least one hinge pin embraced by a torsion spring serving to balance the weight of the guard means.

3. The combination claimed in claim 1 in which the guard means is mounted on at least one hinge pin embraced by a torsion spring of which one end is anchored to a hinge bracket, and in which a safety catch engageable by the hinge bracket serves to retain the guard means against accidental displacement when in its upper position.

4. The combination claimed in claim 1 including a setting-on rod movable to start and stop the machine, a locking box on the front sliver table, a spring-urged detent housed in said box and adapted normally to lie in the path of a locking arm fast on the setting-on rod and projecting beneath the table to a point enclosed by the guard means when the guard means is in its lower position, said detent being engageable with said arm in the upper position of the guard means, and a bracket secured to the inner side of the guard means and formed with a finger adapted to disengage the detent from said arm when the guard means is lowered, said arm engaging said finger on the movement of the setting-on rod to start the machine whereby to lock the guard means in lower position.

5. The combination claimed in claim 1 in which the bottom edge of the guard means is arranged to foul the weighting lever for the detaching rollers of the machine when said rollers have been unweighted, and in which the guard means is provided with a cam-forming block adapted to abut against and move the weighting lever to effect automatic weighting of the rollers.

6. The combination claimed in claim 1 in which a projection is so positioned on the underside of the guard means as to engage a part carrying the top comb of the machine if the top comb should have been raised out of its working position when the guard means has been in its upper position.

7. The combination claimed in claim 1 including projections arranged at opposite sides of the guard means and adapted, when the guard means is in its upper position and nipper-weighting release catches are in raised position, to abut against a handle in operative connection with the nippers and prevent the guard means from being lowered until weighting has been restored to the nippers.

8. The combination claimed in claim 1 including a machine-operating shaft carrying a fly-wheel, a brake-block engageable with said fly-wheel, means normally urging said brake-block towards said fly-wheel, a rocker-shaft, a setting-on rod operable only when the guard means is in its lower position, a linkage between said setting-on rod and said rocker-shaft, means influenced by said rocker shaft and operative on movement of said setting-on rod to start the machine to free said brake-block from said fly-wheel, and to bring about engagement of the brake-block with the fly-wheel when the setting-on rod is moved in the reverse direction, and means operatively connected to said rocker shaft for preventing the suction box lids from being opened while said brake is freed and for preventing the freeing of said brake while a suction box lid is open.

9. The combination claimed in claim 1 including a slide-rod extending lengthwise of and at the rear of the machine, a pulley shaft for operating the machine and carrying fast and loose pulleys, a belt engageable with either of said pulleys, a belt-shifter for shifting the belt from one pulley to the other, a rocker-shaft for the belt-shifter, said rocker-shaft having an operative connection with said slide-rod, arms on said slide-rod, one adjacent to each suction box, and in interfering relation with the suction box lid, and means for operating the belt-shifter and thereby imparting sliding movements to said slide-rod.

DONALD PIERPONT.
